UNITED STATES PATENT OFFICE.

MAURICE L. SINDEBAND, OF NEW YORK, N. Y., ASSIGNOR TO GENERAL RAILWAY SIGNAL COMPANY, A CORPORATION OF NEW YORK.

AUTOMATIC TRAIN-CONTROL SYSTEM.

Application filed July 21, 1921, Serial No. 426,470. Renewed January 4, 1924.

This invention relates to train-controlling systems. More specifically the invention relates to systems in which the speed of a train is decreased to a safe value, or brought to zero, or an indication given when a pre-determined zone of the track ahead of the train is occupied.

One of the principal objects is to provide a system of the class described which is biased to danger, so that on failure of any of the component parts of the system, such as the sources E. M. F. current-conveying conductors, etc., the train will be brought to a safe speed, or a danger indication given, or both.

Another object is to provide a system which may readily be incorporated with way-side signaling systems, either direct current or alternating current, now known and in use.

A further object is to provide a system in which the control, between the track system and cab-contained mechanism, is exercised without the use of ramps, contact shoes, track trips or other mechanism. Other objects and advantages will appear as the invention is hereinafter disclosed.

Referring to the drawings which illustrate what I now consider a preferred form of the invention.

Figure 1 is a diagrammatic view illustrating the way-side or track system; one of the sections or blocks being occupied by a train.

Fig. 2 is a diagrammatic view of the train-carried portion of the invention.

Referring to Fig. 1, it will be seen that I have shown a track consisting of a plurality of blocks or sections, B, B', B'', etc. The opposite rails of each block are insulated from each other, as by being mounted on the usual ties, and the rails on each side are electrically continuous throughout each section. Suitable impedances separate the track into its various blocks or sections. If the road be a steam road these impedances may assume the form of insulation 10 as shown in Fig. 1. If the road be an electric road, inductance or other suitable impedance bonds may be employed in lieu of the insulation 10. In short, the track system is of the sectional rail type. Each block or section B, B', B'', etc., has connected thereto, across the rails at the entering end, the

coil of a corresponding pole-changing relay 55 R, R' or R''. And the opposite rails of each block, at the exit end, are connected to a corresponding one of batteries, or other suitable sources of E. M. F., C, C', C'', etc. The last-mentioned connection is effected 60 through corresponding pole-changers operated by the coils R, R', R''. These will now be described in greater detail.

The relay R is provided with three pairs of front contacts and two pairs of back contacts. One contact of the pair of front contacts 11, 11 is connected to one terminal of the battery C and to a back contact 12, while the other of the pair of contacts 11, 11 is connected to one side of the track section B'. The other side of the battery C is connected to one of the contacts of each of the pairs of back contacts 13, 13 and front contacts 14, 14. The other of the pair of back contacts 13 is connected to the contact 75 11, above-mentioned as being connected to the section B'. The contacts of the pairs 12, 14, other than those whose connections were described above, are connected to each other and to the side of section B' opposite 80 to that connected to contacts 11, 13. When the section or block B is clear (i. e., unoccupied) and conditions are otherwise normal the relay R will be energized (as will hereinafter appear) and the front contacts 85 will be engaged. The circuit through the track section B' will then be as follows: from battery C, through contacts 11, one side of rail section B', relay R', the other side of rail section B', contacts 14, back to 90 the battery C. If the relay R is de-energized, through any cause, its core will drop (by gravity or otherwise) so that the front contacts will be disengaged and the back contacts engaged. The circuit through 95 the track section B' will then be the same as that above traced except that the contacts 13, 13 and 12, 12 are substituted for the contacts 11, 11 and 14, 14, so that the polarity 100 of the opposite rails of the section B' is reversed. The relays R' and R'' are provided with similar contacts, 111 to 114 and 211 to 214, respectively, connected similarly to batteries and section C', B'' and C'', B''', respectively. It will now be understood that 105 when any block or section is normal the rails of the adjacent block in the rear will have a predetermined polarity, and when

- any block or section is abnormal (due for example to the presence of a train in that block) the polarity of the opposite rails of the adjacent section in the rear will be 5 reversed. The relays R, R', R'', are neutral relays: i. e., each of them is capable of maintaining its armatures in the attracted position when energized by current of normal or reverse polarity.
- 10 The system as thus far described may not only be employed to control the train-carried system hereinafter described, but also to control way-side signals. Thus each of the sections B, B' and B'' is shown as provided at, or adjacent, its entering end, or a suitable distance in the rear thereof, with a semaphore or other signal S, S', S''. The signal S is provided with suitable actuating mechanism (not shown) which, when electrically energized, maintains it in "clear" 15 position. When de-energized, the signal assumes its biased position, i. e., it indicates "danger." The signal circuit includes front contacts 15, 15 of relay R and a battery or other suitable source of current G. When the section or block B is clear and otherwise normal, the signal S will be held at clear by current flowing from the battery G through the signal S and contacts 15, 15 20 back to battery. If the section B is occupied by a train or is otherwise abnormal, the relay R will be de-energized and the last-traced circuit broken at contact 15, thus setting the signal S at danger. The connection for the signal S', including contacts 115, 115 and battery G', and the connections for the signal S'', including the contacts 215, 215 and battery G'', will be understood 25 in view of the foregoing description in connection with the signal S.
- The wheels upon one side of a train are commonly connected, electrically, to the corresponding wheels upon the other side through the axles. I have found by actual 30 test, that when a locomotive enters a track section such as sections B, B', etc., the leading or first axle carries about 60 per cent or more of the short-circuit current. In other words, there is quite a difference 35 between the values of the current flowing through the first axle to enter a section B, B' or B'' and that flowing through the last axle of the same locomotive in the same section. This fact should be borne in mind 40 as upon it depends the operation of the system herein disclosed.
- If the road be a steam road I prefer to employ the first truck axle in the direction 45 of traffic and the last axle on the tender as a part of the means for coupling the track circuits and the train-carried circuits. If the road be an electric one, two suitably spaced axles of the train would be employed. Two such axles are designated 20 and 21 in 50 Figs. 1 and 2. I shall now proceed to de-

scribe a preferred form of train- or vehicle-carried instrumentalities forming a part of the invention.

Two identical, or substantially identical, closed cores 22, 23 are suitably mounted 70 upon the vehicle, each surrounding a corresponding one of the axles 20 and 21, respectively. Each of these cores is of iron, selenium steel, or other suitable magnetizable material, and each is preferably laminated. Each of the cores 22, 23 is shown provided with a primary winding 24 or 25, said primary windings being of the same number of turns, wound in the same sense, and serially connected with each other in the same sense across a suitable source of alternating E. M. F., such as an alternating current generator 26. Each of the cores 22, 23 is also shown provided with a secondary winding 29, 30, said secondary windings being of the same number of turns, but serially connected to oppose each other in a circuit including one phase or coil 31 of a two-phase relay 33. The other phase or coil 32 of the relay 33 is connected across the generator 26. The relay 33 is employed to control a vehicle-carried signal, or vehicle-speed-controlling instrumentalities, or both. This may be accomplished by means of the following mechanism.

The relay 33, in one of its positions bridges, or electrically connects, a pair of contacts 35, 35, another pair of contacts 36, 36 being open at this time. In another of its positions, the relay 33 bridges the contacts 36, 36, the other contacts 35, 35 being open at this time. The contacts 35, 35 are shown connected in series with a battery 37 and the coil 38 of an electromagnetically operated valve 39 in the air line or train pipe 40 forming a part of the usual air-brake system mounted upon the vehicle. When the contacts 35, 35 are closed the coil 38 is energized and the brakes are not applied but when the contacts 35, 35 are open the relay 33 is de-energized, the line 40 is opened and the brakes applied.

The parts 22, 23, 24, 25, 29, 30, 31, 32 and 100 33 are so designed that when there is no current flowing in axles 20 and 21 the E. M. F.'s induced in the coils or windings 29 and 30 are exactly equal and opposite so that no current will flow through the coil 31 of the two-phase relay 33. The effect of any current through axles 20, 21 of a frequency lower than that of the alternator 26, is to change flux conditions in the core. At this point it may be stated that any current flowing through axles 20 and 21 is to be regarded as alternating current—direct current being considered as alternating current of zero frequency. If the currents in the axles 20 and 21 were equal and in the same sense, the flux changes in the cores 22 and 23 would 105 be identical so that the voltages induced in 110

windings 29 and 30 would still be equal and no current would flow in phase 31 of the relay 33. However, if the current in the axle 20 exceeds that flowing in the same direction in the axle 21 the E. M. F. induced in one of the windings 29, 30 will preponderate over that induced in the other of said windings and a current will flow through the relay coil 31. The direction of flow of the last mentioned current will depend upon the direction of flow of current through the axles 20 and 21. When the coil 31 is de-energized or when energized by current flowing in one direction, the relay 33 causes the bridge between the contacts 35, 35 to be broken. When the coil 31 is energized by current flowing therethrough in a direction opposite to that above mentioned, the relay 33 closes or bridges the said contacts 35, 35. The operation of the system as thus far described may be explained as follows.

Assume a vehicle to be in block or section B'' and traveling in the direction of the arrow. The relay R'' is then short-circuited and releases its core to open contacts 215, 215, whereby the signal S' is set at danger. The block B' is clear and normal. The relay R' is therefore energized and current flows from the battery C', through contacts 111, one side of track section B'', axles 20, 21, the other side of the track section B'', contacts 114, back to battery C'. The direction of flow of current is indicated by arrows in Fig. 1. Under these conditions the balance between the coils 29 and 30 is destroyed and current flows in such direction in the coil 31 of the relay 33 as to cause the latter to bridge the contacts 35, 35, to maintain the coil 38 energized so that the brakes are not applied. If the battery C' should fail, or should become short-circuited ahead of the vehicles, or the circuit including the battery and rails of section B'' should become broken, there would be no current flowing in the axles 20 and 21. In this event the coil 31 of relay 33 would become de-energized and the contacts 35, 35 would be opened to vent the train pipe 40 and apply the brakes. The system is therefore biased so as to stop the train if abnormal conditions exist. It will be noted also that the signal S' is "clear" when conditions ahead are normal.

Assume now that the vehicle travels ahead and enters the block or section B'. As soon as it passes out of section B'' the relay R'' is re-energized, picks up its core and signal S'' assumes the "clear" position. The block B being clear, the coil 31 is energized in such a direction that the contacts 35, 35 will remain bridged and the vehicle brakes will not be applied, as will be readily understood in view of the foregoing description. Assume now that, with the first train in block B' a second train enters or attempts to enter block B''. The first train will have shunted

out the coil of the relay R' causing the latter to disengage its front contacts and to cause the back contacts to be bridged. Current will then flow through the axles 20, 21 of the second train (in section B'') in a direction opposite to that in which it would have flowed if the block B' were clear. The coil 31 of relay 33 will thus be energized by current flowing in such direction as to cause the relay to open contacts 35, 35 to cause brakes to be applied to the vehicles. Obviously, if the relay R' had been shunted out by something other than a train, or if the battery C should fail, or if either connection between the battery C and relay R' should fail, the relay R' would be de-energized to stop a train in the block B''. If the battery 37 should fail or its circuit become broken in any way, the train carrying that battery would be stopped. If the coil 31 is de-energized due to any cause such as a break in the circuit of the coils 29, 30 and 31, the vehicle would be stopped. If the circuit between the coils 24, 25 and the generator should break, the train would be stopped. In short it will be appreciated that I have provided a system which, in spite of its great simplicity, is thoroughly reliable and which, upon failure of any of its component parts, will stop the train or trains until the cause for failure has been remedied. If any block be occupied by a vehicle, a vehicle in the preceding block will be brought to a stop automatically. In addition to the above mentioned advantages, I wish to point out that, except for such line wires as are required for the way-side signals S, S', S'', etc., no line wires need be employed in my system.

Numerous modifications may be made in the system above described. For example, it may be desirable not to remove the control of the vehicle from the engineer, or motorman, even when the vehicle is in a danger zone but rather to permit him to proceed at a speed such as will permit him to stop the vehicle quickly. This may be accomplished by employing instrumentalities shown at the left of Fig. 2, or the equivalent thereof. In Fig. 2 I have shown speed-controlled contacts 50, 51 shunted across the contacts 35, 35. If the contacts 50, 51 are closed the vehicle brakes will not be applied because of the current flowing through the following path: from battery 37, through contacts 50, 51, electromagnet 38 and back to battery. Means are provided for maintaining the contacts 50, 51 closed so long as the speed of the vehicle is below a predetermined amount, say 15 miles per hour, and for opening the contacts 50, 51, when that speed is exceeded. This means may assume various forms among which is that illustrated.

The pivoted contact 50 is biased away

from fixed contact 51 by any suitable means, such as a spring 52, and is adapted to engage at one end the sliding sleeve 53 of a centrifugal governor 54 driven by any one of the vehicle axles 55 through gearing 56, 57. These parts are designed to operate as follows. When the speed of the vehicle is at or below a predetermined value, say 15 miles per hour, the contacts 50, 51 are maintained closed by the governor 54, through its sleeve 53. If that speed is exceeded, even slightly, the governor 54 elevates its sleeve 53 to permit the spring 52 to disengage the contact 50 from the contact 51. If the means last described be incorporated in the system the operation will be readily understood in view of the foregoing description coupled with the following explanation.

Assume that there is a vehicle in the block B' and a following vehicle attempts to enter block B''. The contacts 35, 35 will then open on the following vehicle and if the contacts 50, 51, were not provided the following vehicle would be stopped automatically. However, by virtue of the contacts 50, 51 and the governor device the following train may proceed at a speed under 15 miles per hour. Under such conditions the contacts 50, 51 would be closed and the electromagnet 38 energized. If, while block B' is still occupied by the leading train, the driver of the following train in block B'' should attempt to exceed the speed limit imposed (i. e., 15 miles per hour), the contacts 50, 51 would open to de-energize coil 38 to cause the brakes to be applied. If the signal S' be placed in the block B'', adjacent the entrance of the block B', its indication would advise the driver of the following vehicle as to whether or not he may enter section B' with safety. If the signal S' indicates "danger" the following driver should stop his vehicle, while if it stands at "clear" he may proceed with safety at full speed.

A cab signal may be employed instead of, or in addition to, the speed-controlling mechanism above described. The control of such a signal may be effected through the contacts 36, 36 of the relay 33. This signal may assume the form of a red, or other suitably-colored, lamp 60 connected in series with the contacts 36, 36 across the battery 37. Bearing in mind that the contacts 36, 36 are bridged whenever conditions ahead are abnormal (due to a train in the block ahead, or failure of one or more of the sources of E. M. F., or breakage of one or more of the electrical conductors, etc.), it will be appreciated that the lamp 60 will be energized so long as the abnormal condition exists. If a train carrying the signal 60 be stopped, either automatically or by manual operation by the driver, because of danger ahead, the lamp 60 will be lit so

long as the danger exists. When the light 60 is extinguished the engineer will proceed.

It is believed that the operation of that part of the system which embodies the elements 20 to 25 and 29, 30, will be understood by those skilled in the art, in view of the foregoing disclosure. I may state, however, that I now believe the theory of such operation to be similar to that set forth in the copending application filed by me on September 20, 1920, Serial No. 411,479.

The sensitivity of the coupling between the track and vehicle-carried portions of the system may be increased or controlled by superimposing fluxes upon the cores 22, 23 by the means shown at the lower right-hand part of Fig. 2, or means equivalent thereto. Coils or windings 71, 72 are provided upon the cores 22, 23, each of these coils being of the same number of turns as the other. These coils are shown as wound in the same direction but serially connected in opposition to each other in a circuit including a variable resistance 73 and a battery or other suitable source of E. M. F. By properly adjusting the resistance 73, the average flux density in the cores 22, 23 may be so selected, with respect to the magnetization curves, as to cause a maximum response in the circuit 29, 30, 31, upon the heretofore mentioned variations in the currents flowing through the axles 20, 21.

It will be noted that my system is not an inductive one in the sense that this term is commonly employed in the art. The effect of currents in the axles or conductors 20, 21 is not to induce currents in the transformer coils from the track circuits but rather to vary flux conditions in the cores 22, 23 to shift the points on the magnetization curves at which the cores operate. The ultimate effect is to create an unbalance in the E. M. F.'s of coils 29, 30, induced by coils 24, 25. The difference between my system and an inductive one will be appreciated when it is borne in mind that unidirectional currents of constant amplitudes (but different amplitudes) in the axles 20, 21 will produce a response in the circuit of coils 29, 30.

As previously stated, either or both of the devices 38 and 60 may be employed. The signal 60, if employed, guides the driver in the operation of his car. The brake-controlling magnet 60, if employed, automatically controls the speed of the vehicle. Either of these devices 38 and 60 may therefore be termed "traffic-controlling means", and it is in this sense that I have employed the last mentioned expression in certain of the appended claims.

In accordance with the provisions of the patent statutes, I have herein described the principle of operation of my invention, together with the apparatus which I now consider to represent the best embodiments

thereof, but I desire to have it understood that the apparatus disclosed is only illustrative and that the invention can be carried out by other means. Also while it is designed to use the various features and elements in the combinations and relations described, some of these may be altered and others omitted without interfering with the more general results and effects outlined, 10 and the invention extends to such use.

What I claim is:—

1. In combination, a railway track divided into a plurality of sections, means for impressing an E. M. F. across the opposite rails of each section, means for controlling the E. M. F. of each section by a section in advance in the direction of traffic, a railway vehicle having spaced conductors which electrically connect the opposite rails of a section occupied by said vehicle, and vehicle-carried means controlled by the relative character of the currents through said conductors for governing the speed of said vehicle.

2. In combination, a railway track divided into a plurality of sections, means for impressing an E. M. F. across the opposite rails of each section, means for controlling the relative polarity of the opposite rails of each section by the section in advance in the direction of traffic, a railway vehicle having spaced conductors which electrically connect the opposite rails of a section occupied by said vehicle, an impedance carried by said vehicle and inductively coupled to one of said conductors, a second impedance carried by said train and inductively coupled to another of said conductors, and means governed by said impedances for controlling the speed of said vehicle.

3. In combination, a railway vehicle having a plurality of spaced conductors each adapted to electrically connect the opposite rails of the track over which said vehicle travels, a transformer carried by said vehicle and inductively associated with one of said conductors, a second transformer carried by said vehicle and inductively associated with another of said conductors, traffic-controlling means carried by said vehicle, and means controlled by electrically opposed windings of said transformers for governing said traffic-controlling means.

4. In combination, a railway vehicle, a magnetizable core mounted adjacent an axle of said vehicle, a second magnetizable core mounted adjacent another axle of said vehicle, a winding on one of said cores and a winding on the other of said cores, traffic-controlling means carried by said vehicle, and means carried by said vehicle and electrically connecting said windings in opposition for controlling the said traffic-controlling means.

5. In combination, a railway vehicle, a

magnetizable core surrounding one of the axles of said vehicle, a magnetizable core surrounding another of the axles of said vehicle, means carried by said vehicle for impressing alternating magneto-motive forces upon said cores, traffic-controlling means carried by said vehicle, and means comprising windings upon said cores for controlling said traffic-controlling means.

6. In combination, a railway vehicle, a magnetizable core surrounding one of the axles of said vehicle, a second magnetizable core surrounding another of the axles of said vehicle, means for impressing alternating magneto-motive forces upon said cores, 70 a track divided into sections, means for impressing E. M. F.'s across the opposite rails of each section of a frequency different from that of said magneto-motive forces, means for governing the E. M. F. of each track 80 section by a section in advance, a winding on one of said cores, a winding on the other of said cores, and means controlled by the E. M. F.'s induced in said windings for controlling the speed of said vehicle.

7. In combination, a railway track divided into a plurality of sections, means for impressing an E. M. F. across the opposite rails of each section, means for controlling the E. M. F. of each section by a section in 95 advance in the direction of traffic, a railway vehicle having spaced conductors which electrically connect the opposite rails of a section occupied by said vehicle, traffic-controlling means carried by said vehicle, and means controlled by the relative character of the currents through said conductors for controlling said traffic-controlling means.

8. In combination, a railway track divided into a plurality of sections, means controlled by a section in advance for causing a direct current to flow through the rails of each section, a railway vehicle having spaced conductors which electrically connect the opposite rails of a section occupied by said vehicle, traffic-controlling means carried by said vehicle, and means comprising vehicle-carried impedances each electromagnetically associated with corresponding ones of said conductors and controlled by direct current 110 flowing through said conductors for controlling said traffic-controlling means.

9. In combination, a railway vehicle having a plurality of spaced conductors each adapted to electrically connect the opposite rails of the track over which said vehicle travels, means for causing current to flow through said conductors, a vehicle-carried winding electromagnetically associated with one of said conductors, a second vehicle-carried winding electromagnetically associated with another of said conductors, means other than said conductors for impressing an E. M. F. upon said windings, 120 traffic-controlling means carried by said vehicle, and means for controlling the speed of said vehicle.

hicle, and means electrically connected to said windings for controlling said traffic-controlling means.

10. In combination, a railway vehicle having a plurality of spaced conductors each adapted to electrically connect the opposite rails of the track over which said vehicle travels, means for causing current of a predetermined frequency to flow through said conductors, a vehicle-carried winding electromagnetically associated with one of said conductors, a second vehicle-carried winding electromagnetically associated with another of said conductors, means comprising a vehicle-carried source of E. M. F. for impressing an E. M. F. upon said windings, traffic-controlling means carried by said vehicle, and means electrically connected to said windings for controlling said traffic-controlling means.

11. In combination, a railway vehicle having a plurality of spaced conductors each adapted to electrically connect the opposite rails of the track over which said vehicle travels, a magnetizable core surrounding one of said conductors, a magnetizable core surrounding another of said conductors, means carried by the vehicle for impressing alternating magneto-motive forces upon said cores, a track divided into sections, means for impressing E. M. F. across the opposite rails of each section, means for governing the E. M. F. of each track section by a section in advance, a winding on one of said cores, a winding on the other of said cores, traffic-controlling means carried by said vehicle, and means electrically connected to said windings for controlling said traffic-controlling means.

40 12. In combination, a railway vehicle having a plurality of spaced conductors each adapted to electrically connect the opposite rails of the track over which said vehicle travels, a magnetizable core electromagnetically associated with one of said conductors, a second magnetizable core electromagnetically associated with another of said conductors, a primary winding upon each of said cores, means for impressing alternating E. M. F. upon said primary windings, a track divided into sections, means for impressing E. M. F. across the opposite rails of each section, means for governing the E. M. F. of each track section by a section in advance, a secondary winding upon each of said cores, a third winding upon each of said cores, means for energizing said third windings, traffic-controlling means carried by said vehicle, and means electrically connected to said secondary windings for controlling said traffic-controlling means.

65 13. In combination, a railway vehicle having a plurality of spaced conductors each adapted to electrically connect the opposite rails of the track over which said vehicle

travels, a magnetizable core electromagnetically associated with one of said conductors, a second magnetizable core electromagnetically associated with another of said conductors, a primary winding upon each of said cores, means for impressing alternating E. M. F. upon said primary windings, a track divided into sections, means for impressing E. M. F. across the opposite rails of each section, means for governing the E. M. F. of each track section by a section in advance, a secondary winding upon each of said cores, traffic-controlling means carried by said vehicle, and means electrically connected to said secondary windings for controlling said traffic-controlling means.

14. In combination, a track divided into sections, means controlled by a section in advance for impressing an E. M. F. across the opposite rails of each section, a vehicle having a conductor adapted to electrically connect the opposite rails of a section occupied by the vehicle, an impedance carried by the vehicle and electromagnetically associated with said conductor, a second impedance carried by said vehicle and comparatively remote from said conductor, means carried by the vehicle for impressing upon said impedances an E. M. F. different in frequency from that of said first named E. M. F., traffic-controlling means carried by the vehicle, and means connected to said impedances for controlling said traffic-controlling means.

15. In combination, a track divided into sections, means controlled by a section in advance for impressing an E. M. F. across the opposite rails of each section, a vehicle having a conductor adapted to electrically connect the opposite rails of a section occupied by the vehicle, a core of magnetizable material carried by the vehicle and electromagnetically associated with said conductor, a primary winding upon said core, a vehicle-carried source of E. M. F. different in frequency from that of said first named E. M. F. and connected to said primary winding, a secondary winding upon said core, a transformer carried by said vehicle comparatively remote from said conductor and having a primary winding and a secondary winding, said last named primary winding being connected to said vehicle-carried source of E. M. F., traffic-controlling means carried by the vehicle, and means connected to said secondary windings for controlling said traffic-controlling means.

16. The combination set forth in claim 1 in which axles and wheels of the railway vehicle constitute the spaced conductors.

17. The combination set forth in claim 2 in which axles and wheels of the railway vehicle constitute the spaced conductors.

18. The method of communicating influences to moving trains in conformity with

traffic conditions, which consists in supplying to the track rails a direct current, detecting the existence and polarity of the magnetic field created by the flow of such current, and 5 producing in a circuit wholly on the train a current of corresponding polarity.

19. The method of communicating control influences to moving railway trains traveling on tracks divided into blocks each having a 10 track circuit, which consists in applying a uni-directional voltage across the track rails at the exit end of each block of a polarity corresponding to the energized or deener- 15 gized condition of the track relay of the block next in advance, producing in a circuit wholly on the car at all points in its travel through a block a voltage which is derived

from and corresponds in polarity with the current flow in the track rails of that block, and utilizing said voltage on the car for govern- 20 ing cab signal or train control mechanism.

20. In a train control system, the combination with a block signal system having polarized direct current track circuit control, of safety apparatus on a car including a circuit wholly on the car and comprising means for producing a voltage in said circuit derived from and corresponding to the polarity and absence of current in said track cir- 25 30

In testimony whereof I hereto affix my signature.

MAURICE L. SINDEBAND.
